AUTOMATIC SPRINKLER HEAD

Arthur C. Rowley, Drexel Hill, Pa., assignor to
Globe Automatic Sprinkler Company, Philadelphia, Pa., a corporation of Pennsylvania

Application June 17, 1948, Serial No. 33,480

2 Claims. (Cl. 169—38)

1

This invention relates to improvements in automatic sprinkler heads and is a continuation-in-part of my copending application Serial Number 663,534, filed April 19, 1946, now abandoned.

The primary object of the present invention is to provide a sprinkler head having relatively simple and effective heat sensitive means for normally retaining the head sealed, the invention residing also in certain novel and functionally desirable mechanical details hereinafter described.

In the attached drawings:

Fig. 1 is a side elevational view of a sprinkler head made in accordance with my invention;

Fig. 2 is a top plan view of the sprinkler head;

Fig. 3 is a section on the line 3—3 Fig. 2, illustrating the sprinkler head in the process of opening;

Fig. 4 is a side elevational view, partly in section, of a modified form of sprinkler head within the scope of the invention;

Fig. 5 is a top plan view of the sprinkler head shown in Fig. 4;

Fig. 6 is a sectional view on the line 6—6 Fig. 4; and

Figs. 7 and 8 are views in perspective of separate elements of the device shown in the immediately preceding figures.

With reference to Figs. 1, 2 and 3 of the drawings, the sprinkler head as therein illustrated comprises a hollow body member 1 having a generally cylindrical inner wall surface 2, a tangentially directed intake port 3 at one end, and an axially directed discharge port 4 at the other end. The intake port 3 is by way of a transverse tubular extension 5 which is provided at the end with external threads 6 for attachment of the sprinkler head in the sprinkler system, said system or immediately adjoining part thereof being indicated in broken lines and designated by the reference numeral 7. Adjoining the threaded extremity the extension 5 is provided with a hexagonal portion 8 for reception of a wrench. It is to be noted that the passage 9 through the extension 5, which terminates in the intake port 3, is conical in form and tapers toward the said intake port.

In the interior of the head 1 is a conical extension 11 having its base 12 at the intake end of the head member, said extension extending axially toward the discharge port 4. The outer terminal end of the extension 11 is formed with a radially extended head 13, and this head is provided with a plurality of ports 14 which are directed toward the port 4 and whose longitudinal axes, if extended would intersect the port at points adjoining the periphery of the latter. The extension 11 forms in the interior of the head member an annular chamber which terminates in a restriction formed by the radially extended head

2

13 of the extension 11. In the present instance the extension 11 is formed by a separately formed conical member which is threaded into the base portion of the head member as illustrated in Fig. 3.

With the arrangement described above, water admitted under pressure to the interior of the member 1 through the intake 3 will, by reason of the tangential arrangement of this intake port, set up a vortical flow of water in the annular chamber around the extension 11. The vortical movement of the liquid is maintained throughout the passage to the discharge port 4. The restriction formed by the head portion 13 of the extension 11 causes the water to discharge through the ports 14 and to form high velocity jets which intersect the discharge port 4 at points adjoining the periphery thereof, and in the area where the flow of water through the port is concentrated by reason of the centrifugal effect of the vortical action referred to above.

The discharge port 4 is normally closed by a closure element 18 in the form of a disk having a rounded side 19 which is adapted to seat in the discharge port 4. A rounded gasket 21 of soft copper or the like is preferably provided for interposition between the seat and the element 18 and functions in well known manner to effect efficient sealing of the discharge port.

In order to maintain the closure element 18 normally in the closing position, a lever 22 is provided having a hooked extremity 23 the end of which engages in a recess 24 in the head member 1 at one side of the discharge opening, that end of the lever being thereby detachably interlocked with the said member. In assembly the lever extends across and substantially parallel to the plane of the opening 4 so that the tip end of a screw 20 threaded into said lever may engage in a suitable recess 15 in the upper surface of the element 18 whereby the said lever may function to hold the closure element to its seat. The outer end of the lever 22 is engaged by a thermo-sensitive link 25, said link being of known character,

including two plate-like elements 26 and 27 respectively which normally are secured in face to face relation by a fusible solder 28. The element 26 of this compound link is apertured for reception of the outer hooked end 29 of the lever 22 and the element 27 of the link is provided at the opposite end with an aperture for reception of the hooked end 31 of an arm 32, the other end 33 of which is inserted in an aperture in the base end of the element 11 as illustrated in Fig. 3. The arm 32 thus functions to anchor the link 25 to the head member whereby the link may function to retain the arm 22 in the position shown in Figs. 1 and 2 to retain the closure element 18 in operative position closing the port 4.

The screw 20 affords a means for regulating the

pressure exerted through the side lever upon the closure element.

In operation excessive heat in the area of the sprinkler head will cause fusion of the solder 28 and a resulting release of the elements 26 and 27 of the link 25. Pressure of the liquid within the sprinkler system then acts to force the closure element 18 and washer 21 away from the port with the lever 22 pivoting around the hooked end 23 in the recess 24 as illustrated in Fig. 3. Separation of the lever 22 from the head will permit discharge of the water in an atomized pattern.

The embodiment of the invention shown in Figs. 5 to 8 inclusive is in essential respects similar to that described above. In this case, however, the hollow body 35 of the sprinkler head is of generally spherical form and the correspondingly shaped interior chamber 36 is provided with a central positioned stem or extension 37 which extends from the bottom of the chamber toward the discharge opening 38. The extension 37 is recessed from its outer end, as indicated at 39, this recess being frusto-conical in form with the wall thereof converging towards the bottom. The recess 39 communicates at the bottom with four passages 41 which enter the sides of the extension 37 below a shoulder 42 and extend diagonally upward to the bottom of the recess 39. Extending upwardly through said recess is a cylindrical pin 43 having a rounded tip 44 which projects somewhat beyond the terminal end of the recess 39 toward the discharge opening 38.

The discharge opening 38 is normally sealed by a closure disk 45 and associated gasket 46. The disk is normally held to its seat at the outer end of the discharge port by means of a compound lever 47 consisting of the two primary parts shown in Figs. 7 and 8 respectively. The part 48, shown in Fig. 7, has a hooked end 49 which engages under the rim of a projecting flange 51 on the body 35 of the sprinkler head surrounding the discharge opening 38. The end edge of the portion 49 is concaved and curved as indicated at 52 so as to conform to the contour of the body member 35 immediately below the flange 51. The manner in which this member 48 engages the body 35 of the sprinkler head is best shown in Fig. 4. The other extremity of the member 48 is provided at the inner side with transversely spaced sockets 53, 53 which lie one on each side of a central recess 54 in the end edge of the member.

The member 55 shown in Fig. 8 is in the form of a simple lever having at one end a centrally located set screw 56. In assembly this set screw seats upon a spherical element 57 which in turn seats in a socket 58 at the center of the closure disk 45, and the lower terminal end of the set screw 56 is recessed to form a concave seat for the sphere 57. As best shown in Fig. 6 the set screw 56 is threaded into a bushing 59 in the lever 55. At each side of the bushing 59 the member 55 is provided with sockets 61, 61 which, in assembly, register or confront the sockets 53 in the member 48 and these sockets receive spherical elements 62, 62 as shown in Figs. 4 and 6. The recess 54 affords clearance for the set screw 56. The opposite end of the member 55 is provided with an upturned hook-like extremity 63 which engages in an aperture 64 in a fusible link 65, the other end of the link being anchored to a hooked arm 66 which extends from the side of the body member 35.

In assembly the lever member 55 is in effect 75

fulcrumed on the spherical element 57, the outer end of the lever being held down by the link 65 so that the other short end of the lever is pressed forcibly against the under side of the member 48 through the intervening spherical elements 62. Adjustment of the set screw 56 gives the desired tension in the elements. Since the lever 55 reacts with the spherical element 57 it exerts downward pressure upon the closure disk 45 holding the disk securely in the port sealing position as shown in the drawings. Fusion of the link 65 releases the lever 55 so that it, together with the member or reactance link 48, falls away freely to release the disk 45 and to permit the pressure inside the sprinkler to displace the disk and to uncover the discharge port 38. Water from the system then discharges from the port 38 directly from the chamber 36 and also with jet action through the passages 41 and recess 39 so as to form a highly atomized discharge.

It is to be understood that the device is subject to further modification in detail without departure from the invention as defined in the appended claims.

I claim:

1. In a sprinkler, a hollow head member having intake and discharge ports, a detachable closure for said discharge port comprising an element seating in and closing said port, a lever extending transversely across the discharge port on the outside of said head and over said closure element, means for detachably interlocking said lever with the head member at one side of the discharge port, heat-fusible means on the other side of said port for retaining the lever in operative position, an element carried by the lever and forcibly engaged with the top of said closure element to retain the latter on its seat sealing said port, said element being adjustable on the lever to regulate the closure-retaining pressure, said lever comprising two parts, one part being in the form of a lever member carrying the adjustable closure-engaging element and fulcrumed through said element upon the closure element, and a reaction link constituting the other part of the lever and having one end interlocked with the head member, one end of said lever member being held by the heat-fusible means and the other end reacting with said link to hold the adjustable element forcibly against the closure.

2. A sprinkler according to claim 1 wherein the lever member is interlocked with the reaction link by way of a plurality of spherical elements seated loosely in recesses in the confronting faces of said member and link.

ARTHUR C. ROWLEY.
